Primary Examiner — Mark Goodwin*(74) Attorney, Agent, or Firm* — Manabu Kanesaka(57) **CLAIM**

The ornamental design for an excavator cabin, as shown and described.

DESCRIPTION

FIG. 1 is a front view of an excavator cabin showing our new design;

FIG. 2 is rear view thereof;

FIG. 3 is a top plan view thereof;

FIG. 4 is a bottom plan view thereof;

FIG. 5 is a left side view thereof; and,

FIG. 6 is a right side view thereof.

The broken line showing of a cabin is included for the purpose of illustrating portions of the excavator cabin and forms no part of the claimed design.
